(57) **CLAIM**

The ornamental design for a distillation column, as shown.

DESCRIPTION

FIG. 1 is a front view of the distillation column of the present invention;

FIG. 2 is a back view of the distillation column of FIG. 1;
FIG. 3 is a side view of the distillation column of FIG. 1, as
seen from the left side of FIG. 1;

FIG. 4 is a side view of the distillation column of FIG. 1, as
seen from the right side of FIG. 1; and,
FIG. 5 is a perspective view of the distillation column of FIG.
1.

The broken lines showing an exemplary connection fitting is
included for contextual purposes and forms no part of the
claimed design.
